(57) **CLAIM**

The ornamental design for a dashboard console for a vehicle, as shown and described.

DESCRIPTION

FIG. 1 is a front and left side perspective view showing a dashboard console for a vehicle according to our design;

FIG. 2 is a front elevational view thereof;

FIG. 3 is a rear elevational view thereof;

FIG. 4 is a top plan view thereof;

FIG. 5 is a right side elevational view thereof;

FIG. 6 is a left side elevational view thereof; and,

FIG. 7 is a front and left side perspective view of the dashboard console for a vehicle shown in FIG. 1 with a road vehicle in broken lines.

Throughout the Figures, broken lines show unclaimed features of the dashboard console for a vehicle, and a road vehicle on which the dashboard console for a vehicle can be used, and form no part of the claimed design. Portions of the article not shown in the drawings, and portions of the article shown in the drawings but not shaded, form no part of the claimed design.
